US00D877078S

(12) **United States Design Patent** (10) **Patent No.:** **US D877,078 S**
(45) **Date of Patent:** **** Mar. 3, 2020**

(54) **BATTERY SEPARATOR**

(71) Applicant: **Daramic, LLC**, Charlotte, NC (US)

(72) Inventors: **Eric H. Miller**, Philpot, KY (US); **M. Neal Golovin**, Owensboro, KY (US); **Ahila Krishnamoorthy**, Jalahalli Bangalore (IN); **James P. Perry**, Utica, KY (US); **J. Kevin Whear**, Utica, KY (US)

(73) Assignee: **Daramic, LLC**, Charlotte, NC (US)

(**) Term: **15 Years**

(21) Appl. No.: **29/683,410**

(22) Filed: **Mar. 13, 2019**

Related U.S. Application Data

(62) Division of application No. 29/580,376, filed on Oct. 7, 2016, now Pat. No. Des. 847,746.

(57) **CLAIM**

The ornamental design for a battery separator, as shown and described.

DESCRIPTION

FIG. 1 is a perspective view of a first embodiment of a battery separator showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is an enlarged view of the identified area in FIG. 4;

FIG. 9 is a perspective view of a second embodiment of a battery separator showing our new design;

FIG. 10 is a front view thereof;

FIG. 11 is a rear view thereof;

FIG. 12 is a top view thereof;

FIG. 13 is a bottom view thereof;

FIG. 14 is a right side view thereof; and,

FIG. 15 is a left side view thereof.

The dot-dash broken lines define the bounds of the claimed design and form no part thereof.

1 Claim, 11 Drawing Sheets
